Wallace E. Parsons and Walter H. Randall,
Waterville, Maine, assignors, by mesne assignments,
to The Canal National Bank of Portland,
Portland, Maine, trustee, a national banking
association

Application April 16, 1945, Serial No. 119,018

Term of patent 14 years

(Cl. D58—13)

To all whom it may concern:

Be it known that we, Wallace E. Parsons and
Walter H. Randall, citizens of the United States
and residents of Waterville, county of Kennebec,
State of Maine, have invented a new, original,
and ornamental Design for Pack for Fragile
Articles, of which the following is a specification,
reference being had to the accompanying drawing,
forming part thereof.

Fig. 1 is a perspective view of a pack for

fragile articles showing our new design and as
seen when the pack is open, and

Figs. 2 and 3 are similar views as seen from
above and below, respectively, when the pack is
closed.

We claim:

The ornamental design for a pack for fragile
articles, as shown.

WALLACE E. PARSONS.
WALTER H. RANDALL.
